Patented Mar. 16, 1920.

UNITED STATES PATENT OFFICE.

ORA A. COLBY, OF LARIMER, PENNSYLVANIA, ASSIGNOR TO WESTINGHOUSE ELECTRIC AND MANUFACTURING COMPANY, A CORPORATION OF PENNSYLVANIA.

TROLLEY SYSTEM.

1,333,607.

Specification of Letters Patent. Patented Mar. 16, 1920.

Application filed February 3, 1915. Serial No. 5,876.

To all whom it may concern:

Be it known that I, ORA A. COLBY, a citizen of the United States, and a resident of Larimer, in the county of Allegheny and State of Pennsylvania, have invented a new and useful Improvement in Trolley Systems, of which the following is a specification.

My invention relates to trolley systems for electric railway vehicles, and it has special reference to trolleys of the sliding-contact pantograph type and to catenary line construction of the double-conductor type.

One of the objects of my invention is to provide a trolley capable of collecting heavy currents at all speeds with a minimum of sparking or burning at the trolley contact surface.

A more particular object of my invention is to provide a current-collecting device with an upwardly projecting portion adapted to make sliding contact with the inner adjacent surfaces of two freely hung contact conductors.

In a pantograph trolley having a contact shoe adapted to engage the under surface of a single contact conductor, there is often considerable chattering and bouncing of the shoe at high speeds, thus reducing the current-collecting capacity of the trolley and causing excessive wear and burning on the contact conductor.

According to my invention, I provide a trolley with a current-collecting device that is adapted to make contact with the inner adjacent sides of two closely hung parallel-extending contact conductors in such manner as to permit of considerable vertical and lateral movement of the trolley without sparking or breaking contact with the trolley conductors. I provide also a catenary trolley structure in which two parallel-extending contact conductors are pivotally suspended from a single messenger cable in such manner as to be forced apart by a current-collecting device adapted to be interposed between them and to make sliding contact therewith.

My invention may best be understood by reference to the accompanying drawing in which Figure 1 is a view, in end elevation, and Fig. 2 is a view, in side elevation, of one form of apparatus embodying my invention; Figs. 3 and 4 are views, in end elevation and in side elevation, respectively, of a modification of my invention, and Fig. 5 is a view,

in end elevation, of another modification of my invention.

Referring to Figs. 1 and 2 of the drawing, a structure is shown comprising a pantograph frame 1, a current-collecting device 2, and a catenary trolley-line structure 3.

The pantograph frame 1 may be of any well known construction, since it pertains to my invention only as it constitutes a necessary means of support for the current-collecting device 2.

The current-collecting device 2, which is carried upon the upper portion of the frame 1, comprises a centrally-located, upwardly-projecting member 4, the lower portion of which is provided with slots 4^a for positioning said member in a manner to be herein-after described. The member 4 serves as a support and guide for a plurality of oppositely disposed curved contact straps 5, which are united at the top and at the bottom of the supporting member 4 and have their middle portions flared outwardly to form curved wedge-shaped contact surfaces 5^a. The central member 4 is slidably carried on a horizontal laterally extending rod 6 by means of a bearing member 7, that is located near its lower edge. Compression springs 8 surround the respective ends of the rod 6 between the bearing member 7 and upper end members 10 of the frame 1 and tend to maintain the member 4 in a central position on the rod 6. Horizontal positioning rods 9 are also provided, said rods being carried between the upper end members 10 of the frame 1 and projecting through the slots 4^a to maintain the member 4 substantially horizontal when the trolley is raised or lowered.

The catenary line structure 3 comprises a messenger cable 11, a plurality of freely suspended rods or hangers 12 depending therefrom, the lower ends of which are provided with suitable clamping members 13 that carry a pair of parallel-extending trolley conductors 14. The contact conductors 14 are alternately supported at suitable intervals by the hangers 12 which are freely suspended in a staggered relation from the messenger cable 11 in such manner that the conductors 14 tend to normally lie in contact with each other.

With the trolley in the raised position, as shown in the drawing, the upward thrust of the wedge-shaped contact shoe 2 forces the

contact conductors 14 apart until a condition is reached where the downward component of the weight of the conductors 14 and hangers 12 balances the upward thrust of the 5 current-collecting device 2.

The springs 8 are of such strength that they may be compressed to approximately one-half of their length before they will offer a resistance equal to the side pressure 10 of one of the contact conductors; therefore, a relatively small lateral movement of the trolley, caused by the swaying of the car upon which the trolley is mounted, will not affect the position of the current-collecting 15 device 2 with respect to the contact conductors 14, as the frame 1 may move an appreciable distance to either side before one of the springs 8 is compressed sufficiently to bodily move the current-collecting device 20 against the side pressure of the opposite contact conductors.

A very large side movement of the frame 1, however, will compress one of the springs 8, move the current-collecting device 2 to one 25 side, raise one of the contact conductors 14, and break contact with the other and allow it to hang freely in a substantially vertical plane with the messenger cable. However, as a lateral movement of the trolley will 30 never cause the current-collecting device to become disengaged from both contact conductors at the same time, the collection of current is uninterrupted by such movements.

When a small downward movement of the 35 trolley occurs, the force of gravity will cause the contact conductors 14 to approach each other and follow the curved surfaces 5^a of the contact shoe 2, thus assuring contact engagement for a limited range of vertical 40 movement of the trolley.

The modification of my invention, shown in Figs. 3 and 4, differs from the form just described chiefly in that the guide member 4, shown in Figs. 1 and 2 as a part of the 45 current-collecting device, is omitted. In this structure, contact straps 15 are made of resilient material in order to provide for a greater movement of the trolley frame 1, without affecting the position of the current- 50 collecting device 17. This form has the advantage of greater simplicity and lightness than the form first described.

The modification of my invention, shown in Fig. 5, differs from the first form only in 55 the detail construction of the current-collecting device 2^a. The current-collecting device 2^a comprises a pair of oppositely-disposed, upwardly extending members 18, which are pivotally mounted on a shaft 19 that is carried by the base 20. The upper portions of the members 18 form curved contact members 18^a which terminate in points 18^b, and the lower portions of the members 18 have shoulders 18^c adapted to limit the rotative 60 movement of the members 18. The base 20

is provided with surfaces 20^a to form stops for the shoulders 18^c of the members 18. A compression spring 21 is provided between the members 18 which tends to force the members apart. 70

The spring 21 is of such strength that it may be compressed to approximately one-half its original length before its reaction is equal to the horizontal component of the weight of one of the contact conductors 14, 75 so that the spring 21 is compressed as the points 18^b spread the contact-conductors 14 until a condition obtains, as shown in the drawing, in which the upward thrust of the current-collecting device 2^a is counterbalanced. 80

With the trolley in its lowered position and the frame 1 collapsed, the spring 21 forces the members 18 apart until the shoulders 18^c on the members 18 engage the stops 85 20^a on the base 20. This movement brings the points 18^b in line so that the edge of a wedge is presented to force the contact conductors 14 apart when the trolley is raised.

The pressure of the spring 21 insures 90 good contact on the trolley conductors 14 during small vertical movements of the trolley, and the rotative movements of the contact members 18 about the rod 19 allows a certain amount of lateral movement of the 95 trolley without displacing the contact conductors 14 or breaking contact engagement with either of them. A large lateral movement of the trolley will swing one contact conductor to one side and break contact 100 with the other, but the members 18 will never be simultaneously disengaged from both trolley conductors under normal conditions.

I do not wish to be restricted to the specific structural details shown as it is evident that the benefits of my invention may be obtained in other structures differing from those described but embodying the principles of my invention. I desire, therefore, 110 that only such limitations shall be imposed as are indicated in the appended claims. 105

I claim as my invention:

1. The combination with a plurality of normally-engaging parallel-extending trolley conductors, of a trolley shoe having wedge shaped members adapted to be moved at right angles to said conductors to separate the same and to make sliding contact therewith, and means for biasing said shoe 115 laterally and toward said conductors.

2. The combination with a plurality of parallel-extending trolley conductors, of a current-collecting device having a wedge shaped, vertically projecting contact shoe 125 adapted to move at right angles to said trolley conductors to force them apart and make relatively broad surface sliding contact with the inner and under adjacent surfaces thereof, and resilient means for biasing said 130

contact shoe laterally and toward said conductors.

3. The combination with a plurality of parallel-extending trolley conductors, of a current-collecting device comprising a vertically projecting resiliently-mounted laterally movable trolley shoe, having a relatively thin upper edge and surfaces diverging from said edge adapted to move at right angles to said trolley conductors to force them apart and make sliding contact with the inner and under adjacent surfaces of said conductors during a relatively wide range of separation thereof.

15 4. The combination with a pantograph

frame, of a current-collecting device mounted thereon and comprising a plurality of substantially wedge-shaped vertically projecting contact straps, a longitudinal centrally-disposed supporting member for said contact straps, and a pair of centralizing springs disposed one at each side of said supporting member.

In testimony whereof, I have hereunto subscribed my name this 26th day of Jan., 25 1915.

ORA A. COLBY.
